[57] **CLAIM**

The ornamental design for a apertured board for use in association with a bean bag tossing game, as shown and described.

DESCRIPTION

FIG. 1 is a front elevational view of the apertured board for use in association with a bean bag tossing game showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is an isometric view thereof.
